HAND-HELD POWER TOOL FOR EFFECTING ELECTRICAL CONNECTIONS

William J. Baker, Reed City, Walter N. Christiansen,
Spring Lake, Richard J. Hurst, Hersey, and Robert W.
Klemm, Reed City, Mich., assignors to Gardner-Denver
Company, Dallas, Tex.

Filed May 9, 1975, Ser. No. 576,528

Term of patent 14 years

Int. Cl. D8—05

U.S. Cl. D8—68

FIG 2

FIG 1

FIG 3

FIG 4

FIG. 1 is a side elevational view of a hand-held power tool for effecting electrical connections showing our new design;

FIG. 2 is a top plan view;

FIG. 3 is a rear end view; and

FIG. 4 is a perspective view.

We claim:

The ornamental design for a hand-held power tool for effecting electrical connections, as shown.
